UNITED STATES PATENT OFFICE.

LONIE DUGAN, OF MIDLAND, ARKANSAS.

STOVE.

Application filed April 19, 1926. Serial No. 103,109.

The present invention relates to a stove of the cooking type and has for its principal object to generally improve upon structures of this nature by providing one which is reliable, simple, efficient, easily assembled and therefore capable of being manufactured at a low cost, durable, and well adapted to the purpose for which it is designed.

A very important object of the invention 10 is to provide an oven in conjunction with the stove disposed therein so that it may be heated evenly on all sides.

Another important object of the invention 15 is to provide an oven which is mounted in the stove without the necessity of using bolts or like fastening elements.

With the above and numerous other objects in view as will appear as the description progresses, the invention resides in certain 20 novel features of construction, and in the combination and arrangement of parts as will be hereinafter more fully described and claimed.

In the drawing:

25 Figure 1 is a front elevation of the stove embodying my invention,

Figure 2 is a detail fragmentary perspective view showing one corner of the stove looking from the inside.

30 Figure 3 is a top plan view of the stove, Figure 4 is a side elevation thereof,

Figure 5 is a vertical section taken substantially on the line 5—5 of Figure 4 looking in the direction of the arrows, and

35 Figure 6 is a vertical section taken substantially on the line 6—6 of Figure 3 looking in the direction of the arrow.

Referring to the drawing in detail it will 40 be seen that the letter A indicates the stove generally which is provided with an upper structure indicated at B and including a pair of warming compartments C which may be utilized for keeping food warm after it has been cooked.

45 The stove proper consists of the bottom 1, front 2, back 3, sides 4 and 5 and the top 6. The front, back, and sides rest in a groove formed in the marginal rib 7 provided around the edge of the bottom 1 so as to up- 50 stand therefrom. The front 2 is provided with an ash pit 8 formed by the casing 9 the bottom of which rests on a flange 10 formed in the front 2. A removable closure 11 is provided at the top of the casing 9. A fire

box 12 is formed in the stove above the ash 55 pit 10, a grating 13 separating it from said ash pit. The top 6 is provided with a suitable number of openings normally closed by lids 14.

A partition 15 extends from the fire box 60 toward the rear of the stove, and a second partition 16 extends from the rear of the stove toward the front thereof below the partition 15. As is shown to advantage in Figure 5 the partition 15 is provided with 65 upwardly curved sides 17 terminating in offset ribs 18 for engaging the depending cleats 19 provided on the top 6. This partition forms a heat and smoke passage beneath the top and leading to the rear of the stove.

This top 6 is constructed with the groove 20 for receiving the front, back, and sides of the stove. The partition 15 is disposed integral with the fire box structure 12 and may be slid from the forward end of the stove 70 into its proper place and held fixed by bolts 22. The partition 16 extends into the grooves formed in cleats 23 extending inwardly from the sides 4 and 5. The top 6 is provided with an L-shaped cleat 24 engageable by the end 25 of the partition 16. This end 25 consists of the rib 26 engageable over the top of the lower portion of the rib 24 and the extension 27 receivable behind the vertical portion of the rib 24. This partition 75 80 85 90 95 100 105 110 115 120 125 130 135 140 145 150 155 160 165 170 175 180 185 190 195 198 199 200 201 202 203 204 205 206 207 208 209 210 211 212 213 214 215 216 217 218 219 100417 100418 100418 100419 100419 100420 100420 100421 100421 100422 100422 100423 100423 100424 100424 100425 100425 100426 100426 100427 100427 100428 100428

hinged at its bottom as at 40 so as to close over this opening 38. A platform 41 is mounted between rollers 42 in the oven and a cable 43 is attached thereto as at 44 and passes over pulleys 45 and 46 and then attached to the door at 47 so that when the door is open this platform is pulled out of the oven so that articles thereon may be readily removed therefrom or other articles 10 placed thereon. When the door is closed the partition is brought back into its proper position as shown in Figure 5 by cable 48 having a weight 49 at one end and passing over pulleys 50 and then attached to the 15 platform 41 as at 52.

A compartment for containing water is attached to the side 4 and indicated by the numeral 53. A cover 54 is placed over this compartment and a suitable spigot 55 is disposed at the bottom thereof. This compartment may be filled with water which will be heated by the stove and may be used as desired by drawing the same through the spigot 55.

Bolts 56 are engaged with the top 6 and bottom 1 so as to hold them in fixed engagement with the front, rear and side. As is shown to advantage in Figure 2 the front and back of the stove is provided with vertically extending grooved cleats 58 at their ends for receiving the sides 4 and 5. It will thus be seen that the joints of the stove will be efficient and strong and that the various parts may be assembled easily during the manufacture of the device and also for repair purposes. The hot air generated in the fire box will pass between the top 6 and partition 15 and then between partition 15 and partition 16 around the oven and out of the pipe 60 formed on the back 3 which may be connected to the stove pipe 61.

While the preferred embodiment of the invention has been described in detail it will be understood that I do not wish to be limited to the particular construction set forth, since the various changes in the form, material, proportions, and arrangement of parts, and in the details of construction may be resorted to without departing from the spirit 50 or scope of the invention as hereinafter claimed or destroying any of its advantages.

Having thus described my invention, what I claim as new is:

1. A stove of the character described including a bottom, sides, front and rear walls and a top, comprising a fire box, a partition formed integral with and projecting outwardly from the side of said fire box, and a retaining member upon the under side of said top adjacent each side edge thereof to receive the side edges of said partition to arrange said fire box in said front wall, said partition forming a heat and smoke passage beneath the top to the rear of the stove.

2. A stove of the character described in-

cluding a bottom, sides, front and rear walls and a top, a fire box of a length equal to the width of the stove, a partition projecting outwardly from and extending throughout the length of one wall of said fire box and 70 having the sides curved upwardly, grooves upon the under face of said top adjacent the side edges thereof adapted to slidably receive the side edges of said partition to hold the same between the side walls with the upturned sides contacting with the under side of the top, and means for securing said fire box in the front wall, said partition forming a heat and smoke passage beneath said top. 75

3. A stove of the character described including a bottom, sides, front and rear walls and a top, a fire box, a partition formed integral with and projecting outwardly from said fire box, and means whereby said partition and fire box may be supported from the under side of said top, said partition forming a heat and smoke passage beneath the top to the rear of the stove, a second partition extending between said side walls beneath and spaced from the first mentioned 90 partition and terminating inwardly of the front walls, the rear of said second partition turning upwardly and engaging the under side of said top to receive, and form a forwardly leading passage for smoke and heat from the first passage, an oven structure extending from the under side of the second partition and opening through one side wall, and a closure element for said oven, said second partition forming a top for 100 the oven.

4. A stove of the character described including a bottom, sides, front and rear walls, and a top, a fire box, a partition formed integral with and projecting outwardly from one side of the said fire box, means whereby said partition and fire box may be suspended from the under side of said top, said partition forming a heat and smoke passage beneath the top to the rear of the stove, a 110 second partition extending between said side walls beneath and spaced from said first mentioned partition and terminating inwardly of the front wall, the rear of said second partition curving upwardly and engaging the under side of said top to receive and form a forwardly leading passage for smoke and heat from the first passage, a pair of spaced transversely extending 115 grooved cleats formed upon the under side of the second partition, an oven structure having lateral longitudinally extending flanges designed to engage the cleats to be slidably suspended beneath the second partition, one end of the oven opening through 120 one wall, and hinged closure means for the open end of the oven.

5. In a stove of the character described including a bottom, sides, front and rear walls, and a top, an oven within the stove and 130

opening at one end through a side wall thereof, a shelf within said oven, means for slidably supporting said shelf, a hinged closure for said oven, a flexible element connected 5 at one end to the upper part of said closure and extending over a revolute element and secured at its other end to the central part

of said shelf to draw said shelf outwardly upon opening said closure, and weight elements attached to and raised by said shelf, 10 when drawn outwardly, to retract the shelf upon closing the closure member.

In testimony whereof I affix my signature.
LONIE DUGAN.
